UNITED STATES PATENT OFFICE.

MELVIN B. CHURCH, OF GRAND RAPIDS, MICHIGAN.

ADVERTISING-CIRCULAR.

SPECIFICATION forming part of Letters Patent No. 372,301, dated November 1, 1887

Application filed February 10, 1886. Serial No. 191,395. (No model.)

To all whom it may concern:

Be it known that I, MELVIN B. CHURCH, of Grand Rapids, in the county of Kent and State of Michigan, have invented a new and useful Improvement in Advertising-Circulars; and I do hereby declare that the following is a full, clear, and exact description of the same.

My invention is an improved advertising-circular, and is adapted to be used in connection with any class of business, and while I have shown it as applied to a particular class of business, I do not restrict myself to its use in this connection.

In the drawings, Figure 1 represents a face view of the circular as folded. Fig. 2 is a perspective view of the circular partially folded.

The circular is composed of three sections and two half-leaves, the half-leaves being formed upon the ends and the three sections being between them. The sections are marked A B C and the half-leaves D E. The sections B C are printed with appropriate advertising-matter upon both sides, and the section A is printed upon the back side in the same manner. Upon the front of the section A is arranged a series of printed slips, the slips of the series overlapping each other, as shown; or they may be applied in any other desirable manner, this not being material. The tints are preferably indicated by marginal words and figures, as represented. The pages are surrounded by suitable borders, so that when they are folded they make a complete page. The page B is folded upon the page C face to face, and the page A is folded against the back of the page B, the side containing the tinted slips being uppermost. The half-leaf D upon the left of the sheet is then folded over on top of the tinted sheet upon one side, and the half-sheet E is folded over in like manner on the opposite side. The half-leaves do not quite meet at the center, so that in the space between them is shown a portion of the tinted series of slips beneath, and these slips can be wholly disclosed by unfolding the two half-leaves. It will be understood that if the circular is used with other classes of goods where there is simply advertising on the page A, or even in the present case, it may be desirable to have the half-leaves meet or overlap slightly, and I do not therefore limit myself to the space left between the two half-leaves. As intimated, instead of tinted slips, samples of materials or illustrations or any suitable advertising-matter may be used on the front side of the page A, according to the class of goods to which the circular is applied.

It will be observed that, while I have shown the circular as having only three whole sections, any unequal number of whole sections may be used with the same effect, retaining always the half-leaves upon either end of the circular and folding them in the manner heretofore described. Any suitable advertising-matter, either illustrations or words, or both, may be printed upon both sides of the half-leaves.

I claim—

1. An advertising-circular composed of an unequal number of sections having half-leaves at the ends adapted to fold over the front of the circular, substantially as described.

2. An advertising-circular composed of an unequal number of whole sections folded as described, a page, A, containing samples or specimens of the matter advertised, and the half-leaves adapted to fold over upon the said page A, substantially as described.

3. An advertising-circular composed of an unequal number of whole sections folded as described, a page, A, containing samples or specimens of the matter advertised, and the half-leaves partially covering said page A, substantially as described.

In testimony whereof I have signed my name to this specification in the presence of two subscribing witnesses.
